(57) **CLAIM**

The ornamental design for a watch, as shown and described.

DESCRIPTION

FIG. 1 is a front view of a watch showing my new design; FIG. 2 is a rear view thereof;

FIG. 3 is a top plan view thereof;

FIG. 4 is a bottom view thereof;

FIG. 5 is a left side view thereof;

FIG. 6 is a right side view thereof;

FIG. 7 is a perspective view thereof;

FIG. 8 is a front view showing twelve o'clock thereof;

FIG. 9 is a front view showing one o'clock thereof;

FIG. 10 is a front view showing one-thirty thereof;

FIG. 11 is a front view showing two o'clock thereof; and, FIG. 12 is a cross sectional view through the center of the cover glass. The cover glass is shown separately for clarity of illustration.

The portions of the article in broken lines are shown for illustrative purposes only and form no part of the claimed design.
